SLIDE PROJECTOR HOUSING

Thomas M. Steinbach, Park Ridge, and Robert M. Simonelli, Des Plaines, Ill., assignors, by mesne assignments, to General Aniline & Film Corporation, New York, N.Y., a corporation of Delaware

Filed Nov. 1, 1965, Ser. No. 87,974

Term of patent 14 Years

(Cl. D61—1)

FIG. 3

FIG. 2

FIG. 1

7-12 - 5 -

7-12 - 4 -

FIG. 7FIG. 6

FIG. 1 is a perspective view of a slide projector housing embodying our new design;

FIG. 2 is a front elevational view thereof;
 FIG. 3 is a rear elevation thereof;
 FIG. 4 is a side elevational view thereof;
 FIG. 5 is a top plan view thereof;
 FIG. 6 is a side elevational view thereof; and
 FIG. 7 is a bottom plan view thereof.

We claim:

The ornamental design for a slide projector housing, substantially as shown.
